(57) CLAIM

The ornamental design for a shower sprayer, as shown and described.

DESCRIPTION

FIG. 1 is a front top perspective view of a shower sprayer showing the claimed design;

FIG. 2 is rear top perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged partial view of A in FIG. 1.

The broken line in the drawings depict the boundaries of the enlarged views and form no part of the claimed design.
